US00D782765S

(12) **United States Design Patent** (10) Patent No.: **US D782,765 S**
(45) Date of Patent: **** Mar. 28, 2017**

(54) **CLEANING DEVICE**

(71) Applicant: **Nice-Pak Products, Inc.**, Orangeburg, NY (US)

(72) Inventors: **Michael Mooney**, Florida, NY (US); **Gerard Anthony Cahalan**, New Milford, CT (US); **Bruce Kevin Bitowft**, South Nyack, NY (US); **Nelson Wong**, Shen Zhen (CN); **Monish Bhatia**, Guttenberg, NJ (US); **Richard McCann**, Montclair, NJ (US)

(73) Assignee: **NICE-PAK PRODUCTS, INC.**, Orangeburg, NY (US)

(**) Term: **14 Years**

(21) Appl. No.: **29/519,416**

(22) Filed: **Mar. 4, 2015**

(51) LOC (10) Cl. **04-01**

(52) U.S. Cl.

USPC **D32/40**

(58) **Field of Classification Search**

(57) **CLAIM**

The ornamental design for cleaning device, as shown and described.

DESCRIPTION

FIG. 1 is a front perspective view of the cleaning device showing our new design in an extended configuration;

FIG. 2 is a right view thereof;

FIG. 3 is a left view thereof;

FIG. 4 is a bottom view thereof;

FIG. 5 is a top view thereof;

FIG. 6 is a rear view thereof;

FIG. 7 is a front view thereof;

FIG. 8 is a front perspective view of the cleaning device in a partially extended configuration;

FIG. 9 is a right view thereof;

FIG. 10 is a left view thereof;

FIG. 11 is a bottom view thereof;

FIG. 12 is a top view thereof;

FIG. 13 is a rear view thereof;

FIG. 14 is a front view thereof;

FIG. 15 is a front perspective view of the cleaning device in another partially extended configuration;

FIG. 16 is a right view thereof;

FIG. 17 is a left view thereof;

FIG. 18 is a bottom view thereof;

FIG. 19 is a top view thereof;

FIG. 20 is a rear view thereof; and,

FIG. 21 is a front view thereof.

The broken lines in the figures show portions of the cleaning device that form no part of the claimed design.

1 Claim, 12 Drawing Sheets
